(Cl. D83—1)

To all whom it may concern:

Be it known that we, Walter Dorwin Teague and Robert H. Ensign, citizens of the United States of America and residents of Annandale, Hunterdon County, and State of New Jersey; and Bronxville, county of Westchester, and State of New York, respectively, have invented a new, original, and ornamental Design for Combination Scalp Cleaner and Massager, of which the following is a specification, reference being had to the accompanying drawing, forming part thereof.

Fig. 1 is a top plan view of a combination scalp cleaner and massager, showing our new design.

Fig. 2 is a side elevational view thereof.

Fig. 3 is a view of the front face thereof.

Fig. 4 is a front elevational view, on a reduced scale of the combination scalp cleaner and massager.

We claim:

The ornamental design for a combination scalp cleaner and massager, substantially as shown.

WALTER DORWIN TEAGUE.
ROBERT H. ENSIGN.
